CLAIM

The ornamental design for a mobile device case, as shown and described.

DESCRIPTION

FIG. 1 is a rear elevational view for a mobile device case, showing my new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken lines indicate portions of the article that form no part of the claimed design.
